UNITED STATES PATENT OFFICE.

JOSEPH JANTUSEK, OF CHICAGO, ILLINOIS, ASSIGNOR TO NORTHWESTERN EXPANDED METAL COMPANY, OF CHICAGO, ILLINOIS, A CORPORATION OF ILLINOIS.

METAL BASKET.

Application filed June 5, 1922. Serial No. 565,938.

To all whom it may concern:

Be it known that I, JOSEPH JANTUSEK, a citizen of the United States, and a resident of Chicago, county of Cook, and State of Illinois, have invented certain new and useful Improvements in Metal Baskets, of which the following is a specification.

The invention relates to metal baskets and more particularly to metal baskets formed of sheet metal and the body of which is made of a slotted, expanded strip. The invention seeks to provide simple and effective means for circumferentially bracing the expanded metal body of the basket and also to provide an improved bottom construction which will retain fine material and can be readily cleaned.

The invention consists in the features of improvements hereinafter set forth, illustrated in the preferred form in the accompanying drawing and more particularly pointed out in the appended claims.

Fig. 1 is a vertical section of the improved basket.

Fig. 2 is an enlarged detail view in vertical section of the bottom construction.

Fig. 3 is an enlarged detail view in vertical section of the upper rim of the basket, and

Fig. 4 is a detail view in horizontal section on the line 4—4 of Fig. 2.

The body *a* is preferably formed of a single section or strip of sheet metal which has been slotted and expanded and the ends of which are united in any suitable manner to constitute the circumferential or side wall of the basket. This expanded metal body is so disposed that the direction of the original slits in the sheet extend vertically of the basket body and the direction in which it has been expanded extends circumferentially thereof. In the form shown, the sheet metal strip has been slotted and expanded to form uniform diamond mesh having two sets of oppositely inclined strands 10 united at their intersections by integral bonds 11. The opposite zig-zag ends of the strip are interfitted and united by a wire lacing 13 woven through the adjacent end rows of the openings, the ends of the wire lacing being suitably fastened in place, preferably by twisting, as indicated in the drawing. If desired the basket body may be formed of expanded metal having vertical strengthening ribs, as indicated at

12 in Fig. 4. The basket body thus constructed is further expanded to form a flaring upper end and preferably also to shape the basket body so that it tapers gradually from top to bottom. This further expansion tightens the wire lacing.

Such a basket body is extremely rigid in a vertical direction but requires circumferential bracing at the top and bottom. Preferably, as shown, the upper edge portion of the reticulated body is bent around a stiffening metal ring 14 and a strip 15 of sheet metal is bent over the portions of the upper ends of the strands which encircle the ring 13 to thereby securely clamp the fabric to the stiffening ring and also form a finishing bead at the basket rim. Preferably the ends of the ring 14 abut but need not be connected and the ends of the strip 15 overlap, as indicated at 15^a.

The bottom *b* of the basket is formed of an imperforate piece of sheet metal and has an edge flange which is interlocked or interfolded with the lower edge portion of the basket body. An imperforate collar *c* fits snugly within the lower end of the basket body. The collar is formed of a strip of sheet metal having its ends interlocked or interfolded to form a seam 16, and its lower edge is preferably flanged and interlocked with the edge flange of the bottom and the lower edge of the basket body. In the preferred construction shown, the lower ends of the strands of the expanded metal body are bent outwardly around a stiffening ring 17 and the edge flanges 18 and 19 of the collar and bottom respectively are similarly bent outwardly about the ring to securely unite the parts and firmly brace the bottom of the expanded metal body. The bottom edge flange 19 extends substantially at right angles to its body and fits snugly against the lower end of the expanded metal body. The flange 18 of the collar is preferably narrower, fits within the flange 19 and is gripped between the ring and body of the bottom.

The imperforate bottom *b* and the collar *c* form a tight lower portion to the basket body which prevent fine material from passing through the openings in its side wall and it also provides a bottom which can be readily and conveniently cleaned. Since the direction in which the body *a* is expanded extends circumferentially, it tends to contract

2
radially so that the strands snugly engage the upper free edge of the collar, and the passing of fine material or the wedging of small pieces between the upper edges of the

5 collar and the strands is avoided. The collar is preferably cylindrical except that its lower edge is provided with a flange 18, as described, and its upper edge portion is inclined outwardly, as shown, to provide a 10 flaring flange 20. The latter is of such size that it tends to slightly expand the metal body of the basket and so aids in maintaining a snug engagement between the free upper edge of the collar and the expanded 15 sheet metal body of the basket. If the metal body of the basket is provided with strengthening ribs, as indicated at 12 in Fig. 4, the collar *c* or at least the upper edge portion thereof should be provided 20 with similar ribs 21 fitting snugly within the same.

The improved construction is extremely strong and light, effectively prevents the escape of fine material from the bottom of the basket and can be readily kept in clean, 25 sanitary condition. Obviously, changes may be made in the details set forth without departure from the essentials of the invention as defined in the claims.

30 1. I claim as my invention:

1. A metal basket comprising a reticulated body, an imperforate bottom and an inner imperforate collar, said body, bottom and collar being united at the base of the basket 35 and said collar having its upper edge in snug engagement with the reticulated body.

2. A metal basket comprising a reticulated body, an imperforate bottom having an upturned flange at its edge overlapping the lower edge of said body, and a separate, imperforate inner collar fixed to said body and extending upward from said bottom and having a free upper edge snugly engaging 40 the inner surface of the reticulated body.

45 3. A metal basket comprising a reticulated body, an imperforate bottom, and a separate, inner, imperforate collar, said bottom and said collar being united to the body of the basket, said bottom having a flange at its edge upturned about and overlapping the lower edge of said body and said collar having 50 its upper and lower edges in snug engagement with the body and bottom respectively.

55 4. A metal basket comprising a reticulated body, an imperforate collar fitting snugly within the lower portion of said body and an imperforate bottom, the lower edges of said body and said collar and the periphery 60 of said bottom having interlocked flanges.

5. A metal basket comprising a body

formed of oppositely inclined strands, stiffening rings about which the upper and lower ends of said strands are folded, an imperforate bottom having an edge flange folded 65 upwardly over the lower ends of said strands and over the lower ring, and a separate inner imperforate collar fixed within the lower portion of the basket and extending upwardly from said bottom and having 70 a free, outwardly flaring upper edge portion snugly engaging said strands.

6. A metal basket comprising a body formed of oppositely inclined strands, stiffening rings about which the upper and 75 lower ends of said strands are folded, an imperforate collar snugly fitting within the lower portion of said body and having a flange bent around the lower ring and over the lower ends of said strands and an imperforate bottom having an edge flange bent 80 over that of said collar.

7. A basket formed of sheet metal and comprising a slitted and expanded strip united at its ends to form a basket body so 85 disposed that the direction of expansion of the strip extends circumferentially of the body, an imperforate bottom having an upturned annular flange at its edge arranged outside of and interfolded with the lower 90 edge of the body, and a separate, imperforate collar fixed within the lower portion of the basket and having its upper and lower edges in snug engagement with the strands of said expanded metal body and said bot- 95 tom respectively.

8. A basket formed of sheet metal and comprising a slitted and expanded strip united at its ends to form the basket body and so disposed that the direction of ex- 100 pansion of the strip extends circumferentially of the body, an imperforate bottom and an imperforate inner collar, the lower edges of said body and collar and the periphery of said bottom having interfolded 105 flanges, and said collar having a flared upper edge portion snugly engaging the strands of said expanded metal body.

9. A sheet metal basket comprising a reticulated body formed of expanded metal 110 having integral U-shaped strengthening ribs extending longitudinally thereof, an imperforate bottom having a flange at its edge upturned about and overlapping the lower edge of the body, and a separate, inner, im- 115 perforate collar fixed within the lower portion of the basket and extending upwardly from said bottom and having its upper edge portion shaped to snugly engage the strands and ribs of said expanded metal body.

JOSEPH JANTUSEK.
